KNIFE OR SIMILAR ARTICLE OF FLATWARE

Alexander Edward Lewis, Brooklyn, N. Y.

Application October 28, 1954, Serial No. 32,864

Term of patent 3½ years

(Cl. D54—12)

Figure 2 is a side elevational view thereof; Figure 3 is an enlarged front elevational view illustrating the element shown in full lines in Figure 1; and Figure 4 is an enlarged side elevational view illustrating the element shown in full lines in Figure 2.

The essential feature of the design resides in the element disclosed in full lines. The back of this element is in the same in appearance as the front thereof as shown in Fig. 1.

I claim:

The ornamental design for a knife or similar article of flatware, substantially as shown, and described.
